Primary Examiner—Robin V Webster*(74) Attorney, Agent, or Firm*—Fitch, Even, Tabin & Flannery(57) **CLAIM**

We claim the ornamental design for a low flow irrigation emitter, as shown and described.

DESCRIPTION

This application is related to co-pending U.S. Utility patent application Ser. No. 12/367,295, filed Feb. 6, 2009.

FIG. 1 is a perspective view of an emitter;

FIG. 2 is a front elevational view of the emitter of FIG. 1;

FIG. 3 is a right side elevational view of the emitter of FIG. 1;

FIG. 4 is a rear elevational view of the emitter of FIG. 1;

FIG. 5 is a left side elevational view of the emitter of FIG. 1;

FIG. 6 is a top view of the emitter of FIG. 1; and,

FIG. 7 is a bottom view of the emitter of FIG. 1.
